[57] **CLAIM**

The ornamental design for a wrist brace for use with computer keyboards, as shown and described.

DESCRIPTION

FIG. 1 is a front elevational view of a wrist brace for use with computer keyboards showing our new design; FIG. 2 is a rear elevational view thereof; FIG. 3 is a right side elevational view thereof, the left side being a mirror image; FIG. 4 is a top plan view thereof; FIG. 5 is a bottom plan view thereof; and, FIG. 6 is a perspective view thereof, the broken line drawing of a wrist strap is for illustrative purposes only and forms no part of the claimed design.

FIG. 1

FIG. 2

FIG. 3

FIG. 4

FIG. 5

FIG. 6
